ELECTRIC-ARC LAMP.

1,139,965.

Specification of Letters Patent.

Patented May 18, 1915.

Application filed May 2, 1906. Serial No. 314,785.

To all whom it may concern:

Be it known that I, FREDERICK WILLIAM GORE, a citizen of the United States, residing at the city of New York, borough of Brooklyn, in the county of Kings and State of New York, have invented a certain new and useful Electric-Arc Lamp, of which the following is a specification.

This invention is an electric arc lamp designed for use on incandescent lighting circuits.

The invention embodies improved means for attaching an electric arc lamp to a lamp socket similar to an ordinary incandescent electric lamp, whereby the arc lamp of this invention may be used on incandescent lighting circuits.

The invention consists, also, in the provision of means, forming a permanent element of an electric arc lamp, for reversing the connections of the lamp in those cases where the polarity of the socket terminal does not correspond with that required by the lamp.

The invention consists, further, of an arc lamp having an inclosing globe constituting one chamber, another chamber in communication with the first chamber, a hollow solenoid plunger positioned for movement within the second chamber, and a coil exterior to the second chamber and within which the solenoid plunger is movable in the well known manner.

It is well known that an inclosed electric arc develops gases, probably principally carbon monoxid. It is desirable to retain such gas or gases around the arc for increasing the luminosity thereof; but under some circumstances and at certain times, the gaseous contents of the globe become diluted by admixture with atmospheric air when the lamp is extinguished as by switching the current off for a few minutes, and then switching on the current. At such times, the admixture of air with the gases produces an explosive mixture in the arc inclosing globe, and should the current be switched into the lamp when such gaseous mixture is present in said globe chamber, the electric arc produced by the separation of the carbons will ignite the gaseous mixture, thus resulting in an explosion which in some instances produces a shock sufficient to derange some of the working parts of the lamp.

The separate chamber employed in the

lamp of this invention is designed and intended to largely overcome this objection. As the gases are formed when the arc is burning, both the globe and the adjoining chamber become filled therewith, and should the current be switched off for a few minutes, atmospheric air passes into the separate chamber, and mixes first with the gas in said separate chamber. The dilution of the gases by mixing air therewith in the separate chamber is a comparatively slow operation, and hence while the current is switched off for a few minutes, atmospheric air does not come into contact with the gases in the arc inclosing globe so as to produce the explosive mixture, nor do the diluted gases pass from the separate chamber into the arc inclosing globe until such gases contained in the separate chamber have become so diluted with atmospheric air that an explosion cannot take place in the arc inclosing globe when the arc is again struck.

For controlling the feed of the upper carbon, I employ mechanism which counteracts the force of gravity on the solenoid core and insures a gradual approach of the upper carbon toward the lower one for the purpose of restoring the arc without mechanical contact between the carbons. Said mechanism in the present lamp is a combined dash pot and retardation device which controls the gravity feed of the upper carbon. The mechanism is, furthermore, peculiar in the following respects: first, the dash pot is characterized by the employment of a single valve operating to control the inflow of air when the parts are moved suddenly by the first onrush of the current, and said valve acts to check the egress of air when the core falls by gravity, and, second, the dash-pot piston remains practically stationary while the cylinder is movable, thus reversing the ordinary dash-pot mechanism.

My arc lamp is of such small dimensions that it is capable of attachment to the usual incandescent lamp socket, with practically no change in the construction thereof.

My new lamp is exceedingly compact, and the parts are so designed that they will occupy minimum space. One form of my arc lamp does not exceed eight inches and a fraction in length, by two inches and a fraction in diameter, the globe being slightly over three inches in diameter.

My new lamp is especially intended for indoor lighting, to replace the cluster of incandescent lamps commonly used, but it is evident that it can be used with equal advantage in outdoor illumination.

Furthermore, a single lamp of my invention secures marked economy in the consumption of current as compared with a cluster of incandescent lamps capable of producing equal illumination.

Figure 1 is a vertical section, with parts in elevation, through an arc lamp embodying my invention, the lamp shown being substantially full size; Fig. 2 is an inverted or bottom plan full size view of the suspending plug shown by Fig. 1; Fig. 3 is a top plan view (full size) of an upper platform employed in the lamp above the magnet or solenoid; Fig. 4 is an elevation of the platform shown by Fig. 3, and showing the full size of said platform, the platform shown by Fig. 4 being inverted as compared with its position in the lamp as shown by Fig. 1; Figs. 5, 6 and 7 are detail full size views of my new clutch, showing the same in bottom plan, side elevation, and top plan, respectively; Fig. 8 is an enlarged detail view showing parts of the dash-pot and retardation device; Fig. 9 is a detail view through a series of three tubes employed in the lamp, two of said tubes forming parts of the dash-pot and retardation device; Fig. 10 is an inverted or bottom plan view of the disk or member from which is suspended the support for the lower carbon; Fig. 11 is a diagrammatic view of the circuit through the lamp.

My new lamp has its working parts housed within an external casing 5, the latter being of any suitable form and material, and also being, preferably, open at its respective ends.

A flanged ring 6 is positioned around the lower part of casing 5, said ring serving as a seat for the edge portion of a globe 7, said edge of the globe being fitted within the flanges of the ring and said globe having engagement with one of said flanges, substantially as shown by Fig. 1. The ring 8 is positioned upon the casing 5, at a point above the ring 6, said ring 8 being secured in place on the casing by any suitable means, such, for example, as the screws 9. Said ring 8 is deflected or inclined outwardly intermediate its ends, so that the lower part 8^a of the ring is of greater diameter than the upper part thereof, whereby the upper part 8 of the ring is adapted to embrace, and to be secured firmly to, casing 5, while the lower and enlarged part of the ring fits around, and extends below flanged ring 6, see Fig. 1. In the enlarged lower and free part of the ring 8 are the clamping screws 10, the latter engaging with the globe 7, and 65 adapted to hold the latter firmly in place.

The lower casing 11 is positioned, at its upper portion, within the lower open end portion of casing 5, and, also, within the inner flange of ring 6, said casing 11 being attached in a suitable manner to the ring, 70 so as to be held in position thereby. The casing 11 extends into the upper part of globe 7, and the end portions of said casing 11 are closed by means of the plates or disks 12, 13, the same being made, preferably of 75 mica, or any other appropriate insulating material, suitable for the purposes of my lamp.

Obviously, the casing 11 may be secured to ring 6 by screws or rivets (not shown), 80 and as ring 6 is connected to casing 5, it is evident that the casing 11 is connected to casing 5 by means of said ring 6. The plate or disk 13 engages with the lower part of a solenoid 14, the latter being housed within 85 casing 5. The other disk 12 is fitted to the lower part of the casing 11, and is clamped against the edge portion of said casing by a suitable ring 15, the latter serving to secure a tight joint between the disk 12 and the 90 casing 11.

The casing 11 and disks 12, 13, form a substantially closed gas chamber 16, said chamber being positioned substantially between the globe chamber and the chamber 95 provided by casing 5.

The disk 12 which forms the bottom of chamber, 16, is provided with a bushing, 22^a, through which the upper carbon, A, is adapted to pass, and this bushing establishes communication between chamber, 16, and the chamber, 7^a, of globe, 7. The disk, 13, forms the top wall of chamber, 16, and in the center of said disk, 13, is an opening in which the member, 14^a, of a plunger is 105 adapted to work. The opening in disk, 13, is nearly filled by plunger, 14^a, but it is evident that air can enter chamber, 16, through said opening in disk, 13, although the inflow of air or the outflow of gases from said 110 chamber, 16, takes place in very limited quantities. It will be observed that the globe 7 provides a chamber 7^a, within which the carbons A, B, are arranged to produce the electric arc, the gases resulting from the 115 production of the arc being collected by or within the chamber 7^a and more or less of said gases flow from said chamber, 7^a into the diluting and collecting chamber, 16. The chamber 16, which is formed by the 120 casing 11, and the disks 12, 13, is separate from the chamber 7^a of the globe, and in this chamber 16 is adapted to be stored some of the gases which result from the arc. The lower or negative carbon B is fitted in 125 a socket at the lower part of the metallic yoke 17, the latter being attached to, and suspended from, the insulating disk or plate 12 at the bottom of the gas chamber 16.

It is preferred to make the legs of the 130

6 yoke 17 quite thin in cross-section, in order that the yoke may not cast any appreciable shadow when the lamp is in service, but the end portions of this yoke are round, in order that they may fit within the thimbles 18.

7 Each thimble 18 has a clamping screw 19 mounted therein, said screws engaging frictionally with the end portions of the yoke 17, for the purpose of detachably clamping 10 said yoke to the platform 12. A binding screw 20 extends through the insulating disk 12, and has electrical contact with one of the thimbles 18, and this screw 20 has metallic contact with a wire 21, which 15 forms a part of the negative lead of the lamp, the current flowing through the negative carbon, the yoke, one of the thimbles 18, and the conductor 21.

Extending upwardly from the member 13 20 is a stationary tube 22, around which is coiled the solenoid 14, the latter being covered as usual with appropriate material which is engaged by screws 9, said screws being supported in casing 5 and operating to retain 25 the magnet in a fixed position therein. The magnet or solenoid extends upwardly from the member 13, so as to occupy, practically, the whole space within the casing 5, and between said member 13, and an insulating 30 platform 23, the latter being made of porcelain, fiber, or any other appropriate insulating material. This platform 23 occupies a stationary position within casing 5, said platform being obviously secured to the casing 35 by suitable screws (not shown). The platform is positioned within casing 5, close to the upper open end thereof and above the solenoid 14, the upper end of the tube 22 being fixed to said platform in any appropriate way.

On the under side of the platform is supported a non-metallic resistance 24, the same consisting of any suitable material, such as carbon, adapted to answer the purpose, and 45 being of any appropriate shape and dimensions. The resistance 24 is fitted against the platform 23, and attached thereto by suitable screws, one of which is indicated at 58, in Fig. 3. The resistance is in the positive lead of the lamp, so as to be between 50 the positive contact and the magnet 14. On the upper side of the platform 23 are parallel ribs or flanges 26, 27, the same being disposed on the respective sides of the opening 55 27^a, for the tube 22, see Fig. 3. Between the flanges 26 is a metallic plate 28, which is secured in place by a screw 29. Another plate 30 is held between the other pair of flanges 27 by a screw 31, and these two plates 60 28, 30, have upstanding members which are adapted for engagement with other plates 32, 33, respectively. Said plates 32, 33, are secured to a plug 34, which is provided with male threads, and is adapted to be screwed 65 into a socket 35 (see Fig. 1), which is in-

cluded in an incandescent lighting circuit 36. The plug 34 has an integral head 34^a, and said plug is, furthermore, provided with a cavity or chamber 35^a. The metallic plate 32 extends along the bottom face of the head 34^a, thence lengthwise of the plug within the chamber 35^a thereof, and along the bottom face of the end portion of said plug 34, at which point a screw 36^a is attached to said plate 32, for the purpose of making connection therewith from one contact 37 of the lamp. The plate 32, within the chamber 35^a, of the plug, is insulated electrically at 32^x, see Fig. 1, from contact with the metallic parts of a combined retardation tube and dash-pot, to be presently described. The other plate 33 is secured on the lower side of the head 34^a of the plug by a screw 39, the latter having engagement with an exposed metallic plate 38, forming the other contact for the lamp. The two plates 32, 33, have depending members adapted to lap the up-standing members of the plates 28, 30, and said members of the four plates are connected detachably together by screws 40, whereby the plates 32 and 33 are adapted to form one pair within the lamp, and the other plates 28, 30, form another pair of plates within the lamp. Suitable holes or slots are provided in the casing 5 opposite to the screws 40, (see Fig. 1) thus permitting a screw driver, or other implement, to be introduced into the lamp for the purpose of releasing the screws 40, and uncoupling the two pairs of plates 28, 32, and 30, 33, whereby the plug 34 may be detached and reversed, for the purpose of bringing the plate 32 into engagement with the plate 30, and the plate 33 into engagement with the plate 28, thus making provision for reversing the leads or connections of the lamp relative to the incandescent circuit.

70 The plug 34 provides a convenient means for interposing the arc lamp in an incandescent circuit, because this plug is adapted to be screwed into the socket 35, so as to bring the two contacts 37, 38, of the lamp into electrical engagement with corresponding contacts of the socket 35, in a manner well understood by those skilled in the art of electric lighting.

75 The plug 34 with contacts 37, 38 and plates 32, 33, attached rigidly thereto, is unitary in construction, thus enabling said plug, the plates and the contacts to be handled and manipulated as a single element when it is desired to reverse the lamp connections. The plug thus performs a two-fold function, first, as a hanger for the lamp, and second, as a means whereby the lamp connections 80 may be reversed. The plug 34 serves the purpose of a hanger for suspending the arc lamp from the socket, and it is evident that the lamp can be easily removed by simply unscrewing the plug from the socket, and,

furthermore, that the lamp can be easily and quickly replaced by simply screwing the plug into the socket.

- The plunger 14^a is a hollow cylindrical mass of soft iron arranged to have endwise movement within the tube 22, and the coil or magnet 14, and through this plunger passes the positive carbon A, the latter being of less diameter than the bore of the plunger, so as to play easily therein. A metallic tube 41 and the plunger lap each other, and are connected together, for simultaneous movement, by suitable pins or studs 42. The tube 41 passes through and beyond the tube 22 and the platform 23, so as to extend into the chamber or cavity 35^a of the plug 34. Within the upper part of the tube 41 is placed a double acting valve, thus making a combined retardation device and dash-pot. The tube 44 is housed within the tube 41, and it is open at its lower end, for the free reception of the carbon A, the latter being thus adapted to pass through the hollow plunger, the tube 41, and into tube 44, as shown by Fig. 1, whereby a compact construction of lamp is secured. The upper part of the tube 44 has a head 44^a, which closes the upper end of the tube 44 (see Fig. 8). Within the upper end of the tube 41 is secured another head 45, the latter being provided with an air opening and a valve seat. Above the head 45 is a disk 46, having another air opening 47 and a valve seat, the latter being on the under face of the disk 46. Between the head 45 and the disk 46 is a check valve 48, which is adapted to occupy one or the other of the valve seats, said seats being provided in the opposing faces of the head 45 and the disk 46. The moving tube 41 is provided intermediate its ends with longitudinal slots 66, see Fig. 9, and through these slots extend screws 65, said screws being supported in bracket lugs 60 fixed to the under side of platform 23. The screws 65 engage firmly with the non-sliding tube 44, for the purpose of holding said tube 44 and its head 44^a in a stationary position. By providing slots in tube 41, said tube is adapted to move with plunger 14^a and to impart movement to heads 45, 46, relative to the head 44^a of tube 44. It is to be understood that tube 44 and its head 44^a constitute the piston member of the combined retardation device and dash pot, the moving members thereof being the tube 41, heads 45, 46, and valve 48, said moving members being actuated directly by plunger 14^a. 50 designates a clutch adapted to engage with the upper carbon A, for the purpose of controlling the gravity feed thereof. This clutch is represented by Figs. 5, 6 and 7 in the form of a split ring, preferably made from sheet metal, by stamping the same. Clutch ring 50 is shown as having a radial slot 51, see Figs. 5 and 7, the purpose of

which is to enable an operator to so bend a part of the ring that the edge will bite against the carbon, but for the purpose of illustration in Figs. 5, 6 and 7, I have shown all parts of said ring in the same plane. The 70 clutch is provided with an upstanding arm, 52, which is pivoted by a pin 54 to a clutch carrier 53, see Fig. 6. The clutch carrier is in the form of a ring or collar having a female thread, and a rearwardly extending 75 arm, the latter being indicated at 55. The carrier is screwed on to a threaded lower portion 14^b of the plunger 14^a, whereby the clutch carrier is attached rigidly to said plunger so as to be supported directly thereon, and to be movable therewith. The arm 55 of the clutch carrier provides for the pivotal attachment of the clutch 50 to said carrier, and said arm 55 also serves as a support for a spring 56, the function of which is to primarily prevent the clutch from being thrown out of gripping engagement with the carbon A at the time when the current is first admitted to the lamp. As shown in Figs. 5 and 6, the spring is fastened to the 80 arm of the clutch carrier. Said spring acts against the upper end of the clutch arm 52. By providing the clutch with the arm 52, and pivoting said arm to the clutch carrier at a point above and to one side of the vertical plane of the clutch ring, said clutch is made to tilt or drop to an inclined position slightly away from the carbon so that the ring will bind or impinge against said carbon, thereby securing the desired frictional 90 engagement of the clutch with the carbon. By pivoting the clutch as described, and employing the spring 56, the clutch is held in engagement with the carbon firmly during the first onrush of the current, whereby the 95 clutch is not disengaged from the carbon under the conditions recited, nor will the carbon be accidentally released from the clutch. The spring 56 does not control the clutch throughout the range of its movement, but the function of the spring is largely to overcome the sudden movement of the clutch when the current is first admitted. The carrier 53 and the pivoted spring-pressed clutch 50 are movable with the plunger 14^a, but the downward movement of the plunger is limited by a short post 57, the latter being attached to the arm 55 of the clutch carrier and extending downwardly 100 therefrom, so as to have engagement with the plate or member 12, when the plunger reaches the limit of its downward movement. This post 57 lies quite close to the arm 52 of the clutch, and the backward or rearward movement of the pivoted clutch, when the 105 carbon is not in place, is limited by this post 57, which is in the path of said clutch, for the purpose of preventing it from swinging rearwardly too far.

The connections are as follows:—From the 130

positive contact 37, the current is adapted to pass into the lamp through the screw 36^a, the plate 32, the screw 40, the plate 28, and thence across by a wire 57^a to a screw 58, (see Fig. 3), through the resistance 24, by the wire 59, to the screw 25, thence through the magnets to a screw 65, and thence by a screw 65, into the tube 44. From the head 44^a of this tube extends a flexible conductor 61, which is attached to the carbon carrier 62, the latter engaging with the upper carbon A. The current traverses the negative carbon B, one leg of the yoke 17, one socket 18, the screw 20, and the negative lead 21, the latter being attached, by a screw 63, to the platform 23 (see Fig. 3). From this screw 63 leads a conductor 64 to the negative contact 30, whereby the current is adapted to pass through said contact 30, and the screw 40 to the plate 33, the screw 38 and the contact 39.

In striking the arc, when the current is first admitted to the lamp, the flow of the current through coil 14 energizes the latter to establish a magnetic field. Prior to switching on the current, plunger 14^a, and the parts associated therewith, occupy their lowermost positions, but when the magnetic field is established, by energizing coil 14, as previously stated, said plunger is drawn upwardly into the coil. This initial upward movement is a comparatively quick or sudden one, and this movement is communicated by the plunger to tube 41, heads 45, 46, and valve 48, the latter being confined between heads 45, 46. The quick movement of tube 41 and heads 45, 46 relative to the head 44^a of stationary tube 44 decreases the air pressure within the dash pot chamber (formed by tubes 41, 44, and heads 45, 44^a) to a point below atmospheric pressure owing to the increase in the cubical area of the dash pot chamber by the relative movement of tube 41^a to tube 44, thus establishing a partial vacuum in the dash pot chamber. The difference in pressure of the air in the dash pot chamber and the air at atmospheric pressure tends to force valve 48 to its seat in head 45 on the upward movement of tube 41 and heads 45, 46 with plunger 14^a, and thus the rapid inflow of air at atmospheric pressure to the dash pot chamber is precluded, whereby the continued quick upward movement of the plunger is checked by the action of the dash pot mechanism.

When the strength of the current in coil 14 decreases, owing to an increase in the resistance of the arc due to partial consumption of the carbons, the plunger 14^a, tube 41, and heads 45, 46, of this lamp have a tendency to descend quickly, owing to the fact that these parts are rather heavy. This tendency is, however, checked, and to a marked extent, by the action of this mechanism, which for convenience in designating

it, I have termed a retardation device as well as a dash pot mechanism, for the reason that said device operates to materially lessen the speed of descent of plunger 14^a, and the tube 41. Upon the downward movement of plunger 14^a and its attached tube 41, head 45 approaches head 44^a of the stationary tube 44, and air confined within the dash pot chamber is compressed by this relative movement of head 45 to head 44^a, such air pressure within the chamber exceeding the air at atmospheric pressure. At first, the air escapes through the ports in heads 45, 46, but as the air pressure increases within the dash pot chamber, valve 48 is lifted by the increased air pressure so as to close port 47 in head 46, thus confining the air in the dash pot chamber. The air confined in the chamber serves as an elastic cushion to the movement of plunger 14^a and tube 41, so that the plunger cannot descend rapidly, and thus the plunger moves downwardly at slow speed, so as to make carbon, A, gradually approach B for the purpose of bringing their ends into such close relation, but without coming into actual or mechanical contact, that the current can flow from one carbon to the other in order to restore the arc.

By reference to Fig. 1 it will be noted that tube 22 is open at both ends, the lower end of said tube being in communication with gas diluting chamber 16 and the upper end of the tube opening into the chamber of casing 5 formed between platform 23 and head 34^a of the attaching plug 32, said chamber being in communication with the outside atmosphere by holes or slots provided in casing 5 opposite to the screws 40. Furthermore, hollow plunger 14^a operates partly within said diluting chamber 16 so that a part of the gases in said chamber 16 may flow upwardly between tubes 41, 42 into the atmosphere through the chamber between plug 34 and platform 23 and the apertures in the casing 5.

Air can flow slowly into chamber 16 through the path above described for the purpose of diluting the gases in said chamber 16, but as the chamber 16 is intermediate the air inlet and the arc-inclosing globe, atmospheric air cannot flow directly into the latter chamber, but any inflowing air first mixes with the gases in chamber 16 so that the gases in said chamber 16 become diluted with air, and the mixed air and gases can, under certain conditions, flow from chamber 16 into the arc-inclosing chamber.

Changes in the form, size, proportion, and minor details in construction may be made without departing from the spirit of the invention or sacrificing any of the advantages thereof, and I, therefore, reserve the right to make such alterations and modifications as fairly fall within the scope of my invention.

Having thus described my invention, what

I claim as new and desire to secure by Letters Patent is:—

1. In an arc lamp, a casing, a hanger plug attached thereto, a platform within said casing, circuit terminals on the plug, and circuit contacts positioned on the platform and coöperating with said circuit terminals, said hanger plug and the platform being relatively adjustable one to the other whereby the circuit terminals may be reversed with relation to the circuit contacts.
2. In an arc lamp, a casing, a hanger plug attached to said casing, circuit terminals on said plug, a platform positioned within the casing, and contacts supported on said platform and coöperating with said circuit terminals, said hanger plug and the circuit terminals thereon being reversible with reference to the platform and the contacts thereof.
3. In an arc lamp, a casing, a hanger plug attached to said casing, circuit terminals on said plug, a supporting member in fixed position within said casing, and contacts carried by said supporting member and coöperating with the circuit terminals, whereby the relation of the circuit terminals may be reversed to the contacts by changing the position of the hanger plug.
4. In an arc lamp, a casing, a hanger plug attached to said casing, circuit terminals on said plug, contacts supported on the hanger plug and positioned within the casing, a supporting member within said casing and below said hanger plug, and other contacts carried by the plug, said second named contacts having detachable engagement with the contacts of the hanger plug.
5. In an arc lamp, a casing, a hanger plug detachably fastened to the casing and adapted to be reversed thereon, exposed circuit terminals on said hanger plug, contacts secured to the hanger plug and positioned within the casing, a platform fixed in said casing below the hanger plug, other contacts carried by the platform, and means for detachably connecting the contacts of the platform with the contacts of the hanger plug.
6. In an arc lamp, a casing, a platform therein, contacts carried by the platform, a unitary hanger reversibly connected to the casing, other contacts carried by said hanger and movable therewith, and means for rigidly connecting the two sets of contacts.
7. In an arc lamp, a casing, a solenoid, a set of contacts fixedly supported within said casing and connected with said solenoid, a unitary hanger reversibly attached to the casing, and another set of contacts carried by said hanger and coöperating with the first named contacts, said hanger and the contacts thereof being reversible relative to the casing and the first named contacts therein.
8. An arc lamp having a solenoid, contacts within the lamp and in circuit with said solenoid, a unitary hanger plug reversible with relation to the lamp, and contacts reversible with said plug relative to the aforesaid contacts.
9. An arc lamp having a platform, a solenoid therein, contacts supported by said platform and in series with the solenoid, a unitary hanger so connected to the lamp as to be reversible with relation thereto, and contacts supported by the hanger and reversible therewith relative to the first named contacts.
10. In an arc lamp, a platform provided with contacts, a hanger reversibly connected to the lamp, and other contacts attached to the hanger, said contacts of the hanger coöperating with the contacts of the platform so that a reversal of the hanger will reverse the relation of the contacts.
11. In an arc lamp, a solenoid plunger, a platform, a clutch-carrier on said plunger, a stop member extending from the clutch-carrier and adapted to engage said platform for limiting the descent of said plunger, a ring clutch having an arm pivoted to the aforesaid carrier and positioned for engagement with the platform when the stop member contacts therewith, whereby the clutch releases a carbon as the stop member arrests the descent of the plunger, and means acting on the pivoted end of the clutch to retain it in engagement with the carbon when the plunger is lifted to raise said clutch free from the platform, said stop member being in the path of the pivoted clutch and operating to limit the pivotal movement of said clutch under the pressure of said retaining means.
12. In an arc lamp, a solenoid plunger, a platform, a clutch-carrier on said plunger, a rigid stop member depending from the clutch-carrier and adapted to engage with said platform for arresting the descent of the plunger, a ring clutch movable with the carrier and positioned for engagement with the platform prior to the engagement of the stop member with said platform, said ring clutch having an upstanding arm pivoted to the clutch carrier and means engaging the pivoted end of the clutch when the latter is lifted free from the platform and acting to hold said clutch in an inclined position, whereby the clutch is retained in engagement with the carbon when the plunger is lifted during the first onrush of current into the lamp, said rigid stop member being in the path of the pivoted clutch and operating to limit the pivotal movement of said clutch under the pressure of said holding means.
13. In an arc lamp, a solenoid plunger, a platform, a clutch-carrier on said platform, a stop member depending from the clutch-

- carrier and adapted to engage with said platform for arresting the descent of the plunger, a clutch provided with an upwardly extending arm which is pivoted to the rear part of said clutch-carrier, said clutch having a ring or eye which is adapted to contact with said platform prior to the engagement of the stop member therewith, and a spring acting on the pivoted end of the clutch for retaining it into engagement with the carbon when the clutch is lifted free from the platform by the upward movement of the plunger, said stop member being in the path of the pivoted clutch and operating to limit the pivotal movement of said clutch under the pressure of said spring.
14. In an arc lamp, a solenoid plunger, a stationary platform, a stop movable with the plunger and adapted to engage said platform, and a pivoted clutch, the movement of said clutch when free from a carbon being limited by said stop.
15. In an arc lamp, a solenoid plunger, a swinging clutch movable therewith, and a stop movable with the plunger and operating to limit the endwise movement of the plunger, and, also, to arrest the swinging movement of the clutch when free from engagement with a carbon.
16. In an arc lamp, a carbon clutch composed of sheet metal and comprising an upright member and a single eye or ring extending at an angle from said upright member, said eye or ring being split by a radial slot and one part of the said eye or ring being adapted to be deflected out of the plane of the other part of said ring.
17. In an arc-lamp, a solenoid, a plunger movable therein, and a combined retardation device and dash-pot coöperating with said plunger, said retardation device and dash-pot comprising a movable cylinder-member attached to the plunger and provided with a head having upper and lower air ports, a fixed piston member within the movable cylinder member, and a single valve adapted to be seated by the pressure or suction of the air in the dash-pot and to open and close the upper and lower air ports in the head of the movable cylinder member.
18. In an arc-lamp, a solenoid, a plunger movable therein, and a combined retardation device and dash-pot coöperating with said plunger, said retardation device and dash-pot comprising a movable cylinder-member attached to the plunger and provided with a head having upper and lower air ports, a fixed piston member within the movable cylinder member, said piston member having a tubular body and a head, the latter being opposite to the head of the cylinder member, and a single valve coöperating with the upper and lower air ports in the head of the movable cylinder member, the cylinder member and the tubular body of the piston member being adapted to receive the upper part of the upper carbon.
19. In an arc-lamp, a solenoid, a hollow plunger, and a combined retardation device and dash-pot cooperating with said plunger, said retardation device and dash-pot comprising a tubular cylinder member and a tubular piston member each adapted to receive the upper part of a carbon which passes through said plunger, said cylinder member and the piston member having opposing heads, the head of the cylinder member being provided with a valved air port.
20. In an arc-lamp, a solenoid, a plunger composed of a hollow mass of metal, a movable cylinder united to the upper part of the plunger, said cylinder being closed at its upper end by a head having a port, a single valve controlling said port and operated solely by the pressure or suction of air in the movable cylinder, and a stationary tubular piston within the cylinder and provided with an imperforate head in opposing relation to the valved head of the cylinder.
21. In an arc lamp, a hollow solenoid plunger, a fixed tubular piston member in line with the plunger, and a cylinder member coupled with the plunger, said cylinder member being movable with respect to the piston member and provided with a single valve for controlling the passage of air therethrough.
22. In an arc lamp, a stationary piston-member, a movable cylinder member, and a single valve carried by the cylinder member and adapted to control both the ingress and egress of air to the cylinder member.
23. In an arc lamp, a stationary tubular piston-member closed at one end, a carbon adapted to play therein, a movable cylinder member provided in a closed end with facing valve seats, and a single valve adapted to occupy one seat or the other on a relative movement of the cylinder member to the piston member.
24. In an arc lamp, a stationary piston member, a solenoid plunger, a movable cylinder member closed at one end and coupled with said plunger for movement therewith, said closed end having facing valve seats, and a single valve adapted to occupy either of said seats.
- In testimony whereof I have signed my name to this specification in the presence of two subscribing witnesses.
